WAGON TAILBOARD LATCH

Filed Dec. 11, 1933

INVENTOR
Fred Cooper
BY
Harry Schreder
ATTORNEY

- each hook-like head having an abutment end portion so positioned as to abut against the upper end of an anchor plate while the bar is engaged with said lugs, whereby a yieldable tension is applied to said bars while so engaged.
2. In a tail gate, the combination with a wagon body, a tail gate hinged at one edge to the wagon body and having recesses in its upper edge, anchor plates secured to the outer face of the tail gate in such manner as to have their upper ends projected above said recesses, said anchor plates each having a pair of rearwardly extended slotted lugs with the slots arranged at right angles with respect to each other, and a pair of locking bars each having a hook-like head portion loosely engaging the wagon body and located within a recess, said locking bars being engageable with the slotted lugs, each head portion having an abutment end so positioned as to bear against the upwardly projected ends of the anchor plates while the bars are engaged with the slotted lugs, whereby a yieldable tension is applied to the bars by the engagement of said abutment ends and said plates.

3. In a tail gate, the combination with a wagon body having sides, a tail gate hinged at one edge to the wagon body and having recesses in its upper edge adjacent the ends thereof, plates secured to the upper edges of said sides and having projecting portions so positioned as to extend over the recesses while the tail gate is in closed position, locking bars having approximately hook-like head portions loosely connected to said plates, each head portion having an abutment end, and anchor plates secured to the outer surface of said tail gate and each having a pair of slotted lugs with the slots arranged at right angles to each other, each anchor plate having an upwardly projecting abutment portion opposite to a recess in the tail gate, said locking bars being engageable with said slotted lugs, said abutment ends and abutment portions of the anchor plates being so constructed and arranged as to apply a yieldable tension to the locking bars while in engagement with said slotted lugs. 5 10 15 20
